UNITED STATES PATENT OFFICE

EMILE A. LAURENT, OF DENVER, COLORADO

DESIGN FOR AN AUTOMOBILE SIGNAL LAMP

Application filed September 24, 1929. Serial No. 32,847. Term of patent 14 years.

To all whom it may concern:

Be it known that I, EMILE A. LAURENT, a citizen of the United States, residing at Denver, in the county of Denver and State of Colorado, have invented a new, original, and ornamental Design for Automobile Signal Lamps, of which the following is a specification.

In the drawing the figure is a perspective view of an automobile signal lamp showing

my new design. The opposite side of the lamp is similar to the side that is shown in the drawing.

I claim:

The ornamental design for an automobile signal lamp as shown and described.

In testimony whereof I have affixed my signature.

EMILE A. LAURENT.
